UNITED STATES PATENT OFFICE.

WILLIAM BLOCK, OF NEW YORK, N. Y.

METAL-BENDING MACHINE.

SPECIFICATION forming part of Letters Patent No. 732,260, dated June 30, 1903.

Application filed May 5, 1902. Serial No. 106,042. (No model.)

To all whom it may concern:

Be it known that I, WILLIAM BLOCK, a citizen of the United States, residing at New York, in the county of New York and State of New York, have invented a new and useful Metal-Bending Machine, of which the following is a specification.

The present invention relates to metal-bending machines, and while particularly intended for bending the blanks of linings for flushing-reservoirs and the like it will be perfectly evident that the machine may be employed for bending sheet metal for various purposes.

One of the objects of the invention is to provide a comparatively simple machine by means of which angular bends may be quickly made in sheet metal, said machine being so constructed that a plurality of such bends may be made simultaneously.

Another object is to provide a machine which can be adjusted so that bends may be made in angular relation to and at different distances from each other.

Still another object is to provide a power-driven machine which is partially automatic in operation, so that but one operator is necessary in running the same and it is completely under his control.

The preferred construction of a machine embodying the invention is fully illustrated in the accompanying drawings, and a description thereof is contained in the following specification.

In the drawings, Figure 1 is a perspective view of such machine. Fig. 2 is a horizontal sectional view showing the lower portion of the machine in plan. Fig. 3 is a vertical sectional view showing a blank being operated upon.

Similar numerals of reference designate corresponding parts in all the figures of the drawings.

In the construction shown a suitable frame is provided comprising horizontal sills 10 and end beams 11, to which are connected upright standards 12, that support cross-bars 13. Upon these cross-bars are secured bearings 14, in which is journaled a horizontal shaft 15. This shaft carries a pair of rotatable bending devices in the form of flanged disks 16, that are located between the bearings 14

and are spaced some distance apart with their flanges at the outer sides, as shown. The disks are secured to the shaft so as to be movable therewith, being fastened thereon by means of set-screws 17, whereby they may be adjusted away from or toward each other.

Secured upon the sills 10 are tracks 18, upon which is slidably mounted a base-platform 19, carrying an upright hollow standard 20. In this standard is journaled a vertical shaft 21, the lower end of which is stepped in a bearing 22, the upper end projecting above the standard and carrying a flat work-supporting platen 23. This platen conforms exactly to the shape of the bottom of the article or box to be operated upon, and is therefore preferably rectangular, though it may be of any other configuration desired. It is movable beneath the shaft 15 and between the bending-rollers 16, the opposite edges of the platen constituting bending-shoulders, which coact with said rollers, the flanges of the rollers overlapping the edges, while the inner portions rest upon the same, as clearly shown in Fig. 1. It will be observed that this platen can be revolved so as to bring either of its opposite edges into coacting relation with the rollers, and in case the edges of one set are farther apart than the edges of the other set the rollers can be moved apart, so that they will coact therewith. In order to hold the platen against its revolvable movement, a holding-screw 24 is threaded into a boss 25, formed upon the lower portion of the standard 20, the inner end of said screw being arranged to engage in sockets 26, formed in a collar 27, that is attached to the lower end of the shaft 21, the outer end of said screw carrying a suitable handle 28. Other means may be employed in lieu of the above-described for holding the platen against its rotatable movement.

The means for driving the machine is as follows: A driving-shaft 29 is located contiguous to the machine, said driving-shaft having mounted thereon a pair of spaced loose pulleys 30, between which is arranged a tight pulley 31, and oppositely-running belts 32, driven by any suitable power, run upon these loose pulleys, so as to rotate them in opposite directions, said belts being movable onto the tight pulley, as will be readily understood. The drive-shaft 29 carries another tight pul-

ley 33, about which is passed a belt 34, that runs upon a pulley 35, keyed to a stub-shaft 36, arranged at one end to the machine-frame. This shaft carries at its inner end a pinion 37, which meshes with a rack 38, fastened to the base-platform 19. A belt 39 passes over pulleys 40 and 41, secured, respectively, to the stub-shaft 36 and the roller-carrying shaft 15, so that they will be rotated simultaneously.

10 As a result it will be seen that when one of the pulleys 32 is upon the tight pulley 31 the work-carrying platen will be moved in one direction beneath the shaft 15, while the bending-rollers will rotatably coact with the edges thereof. In like manner when the other belt is upon the tight pulley the same coaction will take place, but in a different direction, and the platen can therefore be moved back and forth.

15 In order to operate these belts, suitable shifters are employed, said shifters comprising shifting-arms 42, slidably mounted upon supports 43 and having fingers 44, that engage on opposite sides of the belts. A separate and independently-movable arm is provided

20 for each belt, and the inner ends of said arms have depending contact-shoulders 45. A longitudinally-movable actuating-bar 46 is arranged along one side of the base-platform 19 and is provided with outstanding abutments 47, arranged in the path of movement of the rack 38, as clearly shown in Fig. 2.

25 One end of this bar is slidably mounted in a suitable guide-boxing 48, and to its upper face is secured an arm 49, that is disposed diagonally to its line of movement, the shoulders 45 of the shifting-arms 42 being arranged in the path of movement of the arm 49, on opposite sides of the same. A hand-lever 50 is pivoted upon a suitable portion of the frame

30 and is pivotally connected to one of the shifting-arms 42, as shown.

35 In operation, assuming the belts 32 running upon their loose pulleys, a blank is placed upon the platen, which is arranged at one side of the bending-rollers. The operator then manually shifts one of the belts upon the tight pulley by means of a hand-lever, whereupon the bending-rollers will be rotated and at the same time the platen will be moved beneath the same. As a result two sides of the blank will be bent at right angles to the bottom.

40 As the platen passes from beneath the shaft 15 and out of coacting relation with the bending-rollers the end of the rack 38 will engage with the rear abutment 47, consequently moving the actuating-bar 46 in a rearwardly direction and shifting the belt from the tight pulley to the loose, thereby stopping the machine. The operator then releases the up-

45 shaft 21 and revolves the platen to bring the other side edges into coacting relation with the bending-rollers, which rollers are moved toward or from each other upon the shaft, so that they will be in proper relation.

50 The operator then by pressing upon the other belt-shifter throws the oppositely-running belt upon the tight pulley, thereby returning

the platen to the opposite side of the machine and beneath the shaft 15, consequently bending the opposite side walls of the blank. As the base 19 approaches the limit of its return movement the rack will engage the other abutment 47, thereby moving the actuating-bar 46 in the opposite direction, and consequently throwing the belt from the tight to the loose pulley, as will be readily understood. It will therefore be observed that an exceedingly simple power-driven machine is provided which may be adjusted to operate upon various sizes and shapes of sheet-metal blanks and that it will make a plurality of bends simultaneously. Furthermore, the entire machine is under the control of a single operator, who may start or stop it at pleasure, said machine, however, being automatically stopped when the limit of its action is reached, thereby avoiding injury and unnecessary delay in operation.

From the foregoing it is thought that the construction, operation, and many advantages of the herein-described invention will be apparent to those skilled in the art without further description, and it will be understood that various changes in the size, shape, proportion, and minor details of construction may be resorted to without departing from the spirit or sacrificing any of the advantages of the invention.

Having thus described my invention, what I claim as new, and desire to secure by Letters Patent, is—

1. In a machine of the class described, the combination with a rotatable bending device, of a base movable transversely to the axis of movement of the bending device, and a platen rotatably mounted upon the base and having a plurality of edges arranged, when the platen is rotated, to be successively brought into coaction with the bending device.

2. In a machine of the class described, the combination with a rotatable bending device, of a base movable transversely to the axis of movement of the bending device, a platen rotatably mounted upon the base and having a plurality of edges arranged, when the platen is rotated, to be successively brought into coaction with the bending device, and means for securing the platen against rotary movement upon the base.

3. In a machine of the class described, the combination with a single rotatable shaft carrying spaced bending-rollers, of a platen slideable transversely of the shaft and between the rollers, the edges of the platen coacting with the rollers, said platen being revoluble to present its opposite edges to the rollers.

4. In a machine of the class described, the combination with a single rotatable shaft, of spaced bending-rollers mounted upon the single shaft and rotatable therewith, and a work-supporting platen movable beneath the shaft, said platen having bending edges coacting with the rollers.

5. In a machine of the class described, the

combination with a single rotatable shaft, of spaced bending-rollers mounted upon the shaft and rotatable therewith, said rollers being adjustable to different positions upon the shaft and movable toward and from each other, and a work-supporting platform movable transversely of the shaft, said platen having bending edges coacting with the rollers and arranged in overlapping relation therewith.

6. In a machine of the class described, the combination with a rotatable bending device, of a work-supporting platform movable transversely of the axis of rotation of the bending device and having a bending edge coacting therewith, and driving means connected to both the bending device and the platen for simultaneously rotating said bending device and moving said platen.

7. In a machine of the class described, the combination with a rotatable shaft carrying a bending-roller, of a revolute platen movable with relation to the bending-roller, said platen having a plurality of angularly-disposed bending edges arranged to be successively brought into coacting relation with the roller upon the rotation of the platen, and means for holding the platen against rotation.

8. In a machine of the class described, the combination with a rotatable shaft carrying spaced bending-rollers, of a revolute platen movable with relation to the bending-rollers, said platen having sets of angularly-disposed bending edges arranged to be successively brought into coacting relation with the rollers upon the rotation of the platen, and means for holding the platen against movement.

9. In a machine of the class described, the combination with a single rotatable shaft carrying spaced bending-rollers, of a platen movable beneath the shaft and between the rollers, the edges of the platen coacting with the rollers.

10. In a machine of the class described, the combination with a single rotatable shaft carrying spaced bending-rollers that are movable toward and from each other, of a platen slidable transversely of the shaft and between the rollers, the edges of the platen coacting with the rollers, said platen being revolute to present the different edges to the rollers.

11. In a machine of the class described, the combination with a rotatable shaft carrying spaced bending-rollers that are movable toward and from each other, of a platen movable beneath the shaft and between the rollers, the edges of the platen coacting with the rollers, said platen being revolute to present the different edges to the rollers, and driving means connecting both the shaft and platen for simultaneously moving the platen and revolving the roller-carrying shaft.

12. In a machine of the class described, the combination with a movable work-support, of a rotatable bending-roller coacting with the support, reversible driving means for moving the work-support in opposite directions, and

reversing mechanism connected with the driving means, and arranged to be engaged and actuated by the work-support to reverse the movement of said support.

13. In a machine of the class described, the combination with a movable base, of a standard secured to the base, a work-supporting platen mounted upon the standard, and a shaft carrying a bending-roller that coacts with the edge of the platen, said base and standard being movable transversely of the shaft.

14. In a machine of the class described, the combination with a movable base, of a standard secured to the base, a work-supporting platen mounted upon the standard, and a shaft carrying a bending-roller that coacts with the edge of the platen, said platen being movable transversely of the shaft and being revolute to present different edges to the action of the bending-roller.

15. In a machine of the class described, the combination with a movable base, of a standard secured to the base, an upright shaft journaled upon the standard, a platen secured to the upper end of the shaft, and a bending-roller that coacts with the edges of the platen, said base and platen being movable transversely of the shaft.

16. In a machine of the class described, the combination with a movable base, of a work-supporting platen revolubly mounted upon and movable with the base, a shaft carrying a bending-roller that coacts with the platen, said platen and base being movable transversely of the shaft, and means for holding the platen against its revoluble movement.

17. In a machine of the class described, the combination with a movable base, of a standard secured to the base, an upright shaft journaled upon the standard, a platen secured to the upper end of the shaft and being thereby revolute, a set-screw carried by the standard and engaging the shaft to hold said shaft against movement, and a bending-roller coacting with the platen, said platen being movable transversely of the axis of the roller.

18. In a machine of the class described, the combination with a sliding base, of a work-supporting platen mounted upon and movable with the base, a shaft carrying a bending-roller that coacts with the edge of the platen, said base being movable transversely of the shaft, and means for simultaneously sliding the base and revolving the roller-carrying shaft.

19. In a machine of the class described, the combination with a movable work-supporting platen, of a rotatable bending-roller coacting with the platen, driving means for moving the platen, and mechanism connected with the driving means for automatically stopping the platen at a predetermined point.

20. In a machine of the class described, the combination with a movable work-support, of a rotatable bending-roller coacting with the work-support, driving means for moving the

- support, and mechanism connected with the driving means for automatically stopping the support at a predetermined point, said mechanism including a stop arranged to be engaged by the work-support.
21. In a machine of the class described, the combination with a movable work-support, of a bending device coacting with the support during the movement thereof, means for driving the work-support, and mechanism actuated by the work-support when in a predetermined position for disassociating the driving means from and stopping the work-support.
22. In a machine of the class described, the combination with a movable work-support, of a bending device coacting with the support during the movement thereof, means for driving the work-support, said means including a shaft, a tight pulley secured to the shaft, loose pulleys located on opposite sides of the tight pulley, oppositely-moving belts passing about the loose pulleys and movable onto the tight pulley, an independently-movable belt-shifter coacting with each belt, and means for separately moving the shifters.
23. In a machine of the class described, the combination with a work-support, of a bending device coacting with the support during the movement thereof, means for driving the work-support, said means including a shaft, a tight pulley secured to the shaft, loose pulleys located on opposite sides of the tight pulley, oppositely-moving belts passing about the loose pulleys and movable onto the tight pulley, an independently-movable belt-shifter.
24. In a machine of the class described, the combination with a shaft carrying a bending-roller, of a base slidably mounted beneath the shaft, a work-supporting platen mounted upon the base and coacting with the roller, a rack secured to the base, a driving-shaft carrying a pinion engaging with the rack, means for revolving the driving-shaft, and automatic means engaged by the base for stopping said driving-shaft.
25. In a machine of the class described, the combination with a shaft carrying a bending-roller, of a base slidably mounted beneath the shaft, a work-supporting platen mounted upon the base and coacting with the roller, a rack secured to the base, a driving-shaft carrying a pinion engaging with the rack, a belt connecting the roller-carrying shaft and the driving-shaft, means for revolving the driving-shaft, and means for stopping the movement of said driving-shaft.

In testimony that I claim the foregoing as my own I have hereto affixed my signature in the presence of two witnesses.

WILLIAM BLOCK.
